(57) **CLAIM**

The ornamental design for an accent chair, as shown and described.

DESCRIPTION

FIG. 1 is a front perspective view and top perspective view of an accent chair, showing my new design;

FIG. 2 is a rear perspective view and bottom perspective view thereof;

FIG. 3 is a front elevational view thereof;

FIG. 4 is a rear elevational view thereof;

FIG. 5 is a left side view, the right side view being a mirror image of FIG. 5;

FIG. 6 is a top plan view thereof;

FIG. 7 is a bottom plan view thereof; and,

FIG. 8 is a front perspective view and top perspective view of the accent chair in a detached state.

The broken lines in the figures are for the purposes of illustrating portions of the accent chair, which form no part of the claimed design.
